RAILWAY BRAKING APPARATUS

Herbert L. Bone, Pittsburgh, Pa., assignor to The Union Switch & Signal Company, Swissvale, Pa., a corporation of Pennsylvania

Application November 10, 1934, Serial No. 752,478

10 Claims. (Cl. 188—62)

My invention relates to railway braking apparatus, and particularly to braking apparatus of the type comprising wheel engaging braking bars extending parallel to a track rail and movable toward and away from the rail into braking and non-braking positions.

More particularly, my present invention relates to apparatus of the type described and claimed in Letters Patent of the United States No. 1,927,201, granted to me on September 19, 1933, and has for an object the provision of means for improving certain features of the apparatus shown in said patent.

I will describe one form of apparatus embodying my invention, and will then point out the novel features thereof in claims.

In the accompanying drawings, Fig. 1 is a view, partly in section and partly in elevation, showing one form of braking apparatus embodying my invention. Figs. 2 and 3 are top plan and left-hand side views, respectively, showing on an enlarged scale the positioning unit U forming part of the apparatus illustrated in Fig. 1. Fig. 4 is an enlarged sectional view of the positioning unit shown in the preceding views.

Similar reference characters refer to similar parts in all four views.

Referring to the drawings, the reference character 1 designates one track rail of a stretch 30 of railway track, which track rail is secured to rail supports 2 mounted on cross-ties 3, only one rail support and one cross-tie being visible in the drawing. Extending parallel to the rail 1, on opposite sides of the rail are two braking bars A¹ 35 and A², each comprising, as usual, a brake beam 4 and a brake shoe 5.

The braking bar A¹ is arranged to be moved toward and away from the rail 1 by means of a lever 7 which is pivotally supported at one end 40 on a pivot pin 8 mounted in the rail supports 2 directly below the rail 1, and the braking bar A² is arranged to be moved toward and away from the rail 1 by means of a lever 9 which is pivotally mounted intermediate its end on the pivot pin 8. 45 The lever 7 is inclined upwardly and extends away from the rail 1 and is provided in its upper surface with a recess 7^a which receives the braking bar A¹. The one end of the lever 9 is likewise inclined upwardly and extends away from the rail 1 at the side of the rail opposite to the lever 7, and the other end 9^b of the lever 9 is inclined 50 downwardly and extends away from the rail 1 below the lever 7. The end 9^a of the lever 7 is provided in its upper surface with a recess 9^c similar to the recess 7^a in the lever 7, which re-

cess receives the braking bar A². As here shown, the braking bars are fastened to the levers by means of bolts 10 which pass through clearance holes in the webs of the brake beams and in the levers, and are provided on the under sides of the levers with lock washers 11 and nuts 10.

The outer or free end of the lever 7 is pivotally connected by means of a pivot pin 12 with the cylinder 13 of a fluid pressure motor M, and the end 9^b of the lever 9 is pivotally connected by 10 means of a pivot pin 14 and an adjustable screw eye 15 with a piston 15 operating in cylinder 13. Formed in cylinder 13 is an inlet port 16 through 15 which fluid pressure, usually air, may at times be admitted to the upper end of the cylinder.

The parts are so proportioned that lever 7 is biased by gravity to swing in a counter-clockwise direction, and that lever 9 is biased by gravity to swing in a clockwise direction. It will be apparent, therefore, that when cylinder 13 is disconnected from the source of fluid pressure and is vented to atmosphere, the levers, at the ends which are connected with the motor M will swing toward each other to the relative positions in which the piston 15 is at the upper end of the 20 cylinder 13, and will thus move the braking bars away from the rail 1 toward their ineffective or non-braking positions in which latter positions they are out of engagement with the wheels of a car or locomotive traversing rail 1. When, however, cylinder 13 of motor M is supplied with fluid pressure, lever 7 will be swung in a counter-clockwise direction, thereby moving the braking bars toward the rail 1 to their effective or braking 25 positions. When the braking bars occupy their braking positions, the brake shoes 5 will engage the opposite side faces of a car wheel traversing rail 1 and will retard the speed of the car.

It is obvious that it is desirable to have the 30 braking bars A¹ and A² accurately positioned with respect to the rail 1 when they are in their ineffective or non-braking positions, in order to insure that the brake shoes 5 will not engage the 35 wheels of cars or locomotives, which should not be retarded while passing through the braking apparatus, and it is also obvious that it is desirable to have the braking bars accurately positioned with respect to the rail 1 when the braking bars are moved to their effective or braking 40 positions, so that cars which are to be retarded may enter the braking apparatus smoothly and without danger of derailment. For accomplishing these desirable results, I provide a positioning 45 unit U embodying my present invention,

which positioning unit also performs the additional function of assisting the force of gravity in returning the braking bar A^2 to its non-braking position after it has been moved to its braking position, as will appear more fully hereinafter.

As here shown, the positioning unit U comprises a supporting bracket 17 which is bolted at its ends to the cross-ties 3 upon which the associated rail supports 2 are mounted. The supporting bracket 17 is formed with an integral upwardly extending cylindrical portion 18 (see Fig. 4), and screwed onto the upper end of this cylindrical portion is a cylindrical member 19 which, together with the cylindrical portion 18, forms a cylinder 20. A locking plate 21 is fastened to the cylindrical portion 18 between two vertical ribs 22 by means of a stud 23, and the upper end of this locking plate extends into one of a plurality of spaced recesses 24 which are formed in the lower edge of the cylindrical member 19, thus preventing the cylindrical member 19 from becoming unscrewed due to vibration and the like. The lower end of the cylindrical portion 18 of the bracket 17 is provided with an inwardly extending annular flange 25 which forms a shoulder 26, and which surrounds a centrally located opening 27. The upper end of the cylindrical member 19 is likewise provided with an annular flange 28 forming a shoulder 29 which surrounds a centrally located opening 30 that aligns axially with the opening 27. Disposed within the cylinder 20 is a tubular member 31 having its upper end closed by an integral end plate 32, and having its lower end partly closed by a cap 33 which is screwed onto the tubular member. The end plate 32 is provided with an annular flange 34 which fits within the opening 30 with some clearance and which forms a shoulder 35. The cap 33 fits the opening 27 with some clearance and forms a shoulder 36. A compressed coil spring 37 surrounds the tubular member 31 and cooperates at its upper end with a washer 38 which, in turn, cooperates with the shoulders 35 and 29. The lower end of the spring 37 cooperates with a washer 39 which is similar to the washer 38, and which cooperates with the shoulders 26 and 36. A spring bolt 40 extends into the lower end of the tubular member 31 through an opening 41 provided in the cap 33, and adjustably screwed onto the upper end of this spring bolt is a nut 42 which is locked in place by a pin 43. Surrounding the spring bolt 40 between the nut 42 and the cap 33 is a compressed coil spring 44 which biases the spring bolt to a position in which the upper side of an integral hexagonal wrench grip 45 engages the under side of the cap 33, and surrounding the spring 44 is a stop sleeve 46 which cooperates with the nut 42 to limit the downward movement of the spring bolt within the tubular member 31. The lower end of the spring bolt 40 is adjustably connected to the lever 9 by means of a screw eye 47 and a pin 48. To permit the necessary motion which is imparted to the spring bolt 40 when the lever 9 rotates about the pivot pin 8, the opening 41 in the cap 33 through which the spring bolt extends into the tubular member 31 is made considerably larger in diameter than the diameter of the spring bolt, and the nut 42 is made in the form of a frustum of a cone. Furthermore, the under side of the cap 33 is rounded as shown, and the upper end of the stop sleeve 46 is sloped upwardly on two sides in a manner to form a fulcrum about which the spring bolt can pivot when the spring bolt is moved downwardly to the position in which

the nut 42 engages the stop sleeve. The stop sleeve is held in the proper angular position in the tubular member 31 to permit the nut 42 to pivot about the fulcrum formed on the upper end of the sleeve, by means of a lock screw 52 which is screwed into the stop sleeve, and the outer end of which extends into a recess 49 provided in the lower end of the tubular member 31. The end plate 32 on the tubular member 31 cooperates with an adjustable stop screw 50 which is screwed through a tapped hole 51 provided in the upper lever 1.

The stop screw 50 is so adjusted that when the lever 1 has been rotated in a counter-clockwise direction, due to its bias, to the position in which the braking bar A^1 occupies the desired non-braking position with respect to the rail 1, this stop screw will move into engagement with the end plate 32, and the spring 37 is made sufficiently stiff and is assembled into the cylinder 19 with sufficient initial compression so that when the adjusting screw moves into engagement with the end plate under the conditions just described, the spring will hold the tubular member 31 in the position shown in Fig. 1. It will be apparent, therefore, that the positioning unit cooperates with the stop screw 50 to accurately position the braking bar A^1 in its non-braking position.

The screw eye 47 is so adjusted that when lever 9 has been rotated in a clockwise direction to the position in which the braking bar A^2 occupies its desired non-braking position, the wrench grip 45 will move into engagement with the cap 33, and will prevent further rotation of this lever in this direction. It will be seen, therefore, that the positioning unit also serves to accurately position the braking bar A^2 in its non-braking position.

It should be pointed out that since the spring 44 constantly biases the spring bolt 40 to the position in which the wrench grip 45 engages the cap 33, the spring 44 acts to assist the force of gravity in biasing the braking bar A^2 to its non-braking position. The stiffness of the spring 44 is sufficient to insure that the combined force due to the bias of this spring and gravity will return the lever 9 to its non-braking position when no fluid pressure is being supplied to motor M even though abnormal friction should develop between the lever 9 and the pivot pin 8, but the stiffness of this spring is not sufficient to prevent counter-clockwise rotation of the lever 9 when fluid pressure is admitted to cylinder 13 of motor M to separate levers 8 and 9 in the manner previously described.

The nut 42 is so adjusted that when lever 9 is rotated in a counter-clockwise direction by motor M to the position in which the braking bar A^2 occupies the desired braking position, this nut will move into engagement with the fulcrum formed on the upper end of the stop sleeve 46, and the screw eye 47 is so adjusted that when the nut 42 is in engagement with the fulcrum formed on the upper end of the stop sleeve 46 and the piston 15 of motor M occupies its projected position, the lever 1 will be rotated to the position in which the braking bar A^1 occupies its desired braking position.

The operation of the apparatus as a whole is as follows: When the braking bars are in their non-braking positions in which they are shown in the drawings and fluid pressure is admitted to motor M, the lever 9 will first rotate in a counter-clockwise direction until nut 42 moves into engagement with the stop sleeve 46, whereupon

lever 7 will then rotate in a clockwise direction until piston 15 has completed its stroke. Both braking bars will then occupy their proper braking positions.

5 When the braking bars have been moved to their braking positions and fluid pressure is vented from motor M, lever 7 will first rotate in a counter-clockwise direction to the position in which the associated stop screw 50 engages the 10 end plate 32 of the stop unit U, after which lever 9 will rotate in a clockwise direction to the position in which the wrench grip 45 of the stop unit engages the end cap 33 on the sleeve 31. In this 15 position of the levers, piston 15 of motor M will occupy its extreme retracted position, and both braking bars will occupy their non-braking positions.

15 I will now assume that the braking bars have been moved to their braking positions, and that a car having extremely wide gage wheels enters the retarder. Under these conditions, the braking bar A¹ will be forced away from the rail toward its non-braking position, thus causing a force to be transmitted through the lever 7 and fluid pressure motor M to the lever 9, which force will tend 20 to rotate the lever 9 in the direction to move the braking bar A² toward the rail past its proper braking position. As was previously pointed out, when the braking bars occupy their braking positions, the nut 42 is in engagement with the sleeve 25 46, and it will be apparent, therefore, that any force exerted on the lever 9 tending to move the braking bar A² toward the rail past its braking position will be transmitted through the spring bolt 40, nut 42, sleeve 46, cap 33, tubular member 31 and washer 38 to the spring 37, which spring 30 will become compressed and will permit the necessary movement of the lever without causing damage to the retarder. A similar action will 35 take place if a car which is to be retarded and which has normal gage wheels enters the retarder and the retarder is out of adjustment so that the braking bar A¹ is closer to the rail than its proper braking position.

40 45 I will now assume that the braking bars occupy their braking positions, and that a car having extremely narrow gage wheels enters the retarder. Under these conditions, braking bar A² will be forced away from the rail 1, and this movement of the braking bar A² will cause the whole lever assembly to rotate in a clockwise direction around the pivot pin 8 against the gravity bias of lever 7 and the motor M. A similar result will occur if a car having normal gage 45 50 55 wheels enters the retarder to be retarded, and the braking bar A² is closer to the rail than its proper non-braking position due to the parts being out of adjustment.

55 60 If a locomotive having exceptionally narrow gage driving wheels passes through the braking apparatus when the braking bars are in their non-braking positions, and thereby forces the braking bar A² farther away from the rail than its non-braking position, the lever 9 will rotate in a clockwise direction, and this rotation of the lever will 65 act through the associated screw eye 47, spring bolt 40, wrench grip 45, cap 33, tubular member 31 and washer 39 of the positioning unit U, to compress the spring 37, thus permitting the lever 70 and cylinder assembly to rotate as a whole in a clockwise direction about the pivot pin 8. It follows that no damage will result to the retarder under these conditions.

70 75 If a locomotive having exceptionally wide gage driving wheels passes through the retarder when

the braking bars are in their non-braking positions, the outside braking bar A¹ will be moved farther away from the rail than its non-braking position, and the force which is then exerted on the spring 37 of the positioning unit by the associated stop screw 50, tubular member 31 and washer 38, will compress this spring and will thus permit the lever and cylinder assembly to rotate as a whole in a counter-clockwise direction about the pivot pin 8, thus again preventing damage to the retarder.

75 80 85 If a car wheel is forced out from between the brake shoes 6 due to too much retardation, and rides up onto the braking bar A¹, the tendency for the lever assembly as a whole to rotate in a counter-clockwise direction about the pivot pin 8 will cause a force to be transmitted through the motor M, the lever 9, the spring bolt 40, nut 42, sleeve 46, cap 33, tubular member 31 and washer 38 to the spring 37. The spring 37 is made sufficiently stiff so that it will not become compressed under these conditions.

85 90 95 If the braking bars should be moved to their non-braking positions when a car is riding on the braking bar A¹, the engagement of stop screw 50 with the end plate 32 of the tubular member 31 will cause the force exerted on the braking bar by the car to be transmitted to the spring 37 which will act to prevent rotation of the braking bar past its non-braking position.

partly closed at the other end by an end cap, means for biasing said tubular member to one position in said cylinder, means carried by the one lever and cooperating with said end plate to limit the movement of said one lever due to its bias to the position in which the associated braking bar occupies a predetermined non-braking position, and a bolt pivotally connected at one end to the other lever and extending into said tubular member through said end cap, said bolt being provided with means which cooperates with said end cap to limit the movement of said other lever due to its bias to the position in which the associated lever occupies a predetermined non-braking position with respect to the track rail.

2. Railway braking apparatus comprising two braking bars located on opposite sides of a track rail, two pivoted levers supporting said two braking bars respectively, a fluid pressure motor for operating the levers to move said braking bars toward the track rail, said levers being biased by gravity to move said braking bars away from the track rail, a fixed cylinder disposed between said levers, a tubular member in said cylinder closed at one end by an integral end plate and partly closed at the other end by an end cap, means for biasing said tubular member to one position in said cylinder, an adjustable stop screw carried by the one lever and cooperating with said end plate to limit the movement of said one lever due to its bias to the position in which the associated braking bar occupies a predetermined non-braking position, a bolt pivotally connected at one end to the other lever and extending into said tubular member through said end cap, said bolt being provided with means which cooperates with said end cap to limit the movement of said other lever due to its bias to the position in which the associated lever occupies a predetermined non-braking position with respect to the track rail, a nut on said bolt within said tubular member, a sleeve in said tubular member cooperating with said nut and said cap to limit the rotation of said other lever in the direction to move the associated braking bar toward the track rail to the position in which the associated braking bar occupies a predetermined braking position, a spring in said tubular member surrounding said bolt within said sleeve for assisting the force of gravity in rotating said other lever in the direction to move said braking bar away from the track rail, and means on said bolt cooperating with said end cap to limit the rotation of said other lever in the direction to move the associated braking bar away from the track rail.

3. Railway braking apparatus comprising two braking bars located on opposite sides of a track rail, two pivoted levers supporting said two braking bars respectively, a fluid pressure motor for operating the levers to move said braking bars toward the track rail, said levers being biased by gravity to move said braking bars away from the track rail, a fixed cylinder disposed between said levers, a tubular member in said cylinder closed at one end by an integral end plate and partly closed at the other end by an end cap, means for biasing said tubular member to one position in said cylinder, an adjustable stop screw carried by the one lever and cooperating with said end plate to limit the movement of said one lever due to its bias to the position in which the associated braking bars occupy a predetermined non-braking position, a bolt pivotally connected at one end to the other lever and extending into said tubular member through said end cap, a nut on said bolt within said tubular member, and a sleeve in said tubular member cooperating with said nut and said cap to limit the rotation of said other lever in the direction to move the associated braking bar toward the track rail to the position in which the associated braking bar occupies a predetermined braking position.

4. Railway braking apparatus comprising two braking bars located on opposite sides of a track rail, two pivoted levers supporting said two braking bars respectively, a fluid pressure motor for operating the levers to move said braking bars toward the track rail, said levers being biased by gravity to move said braking bars away from the track rail, a fixed cylinder disposed between said levers, a tubular member in said cylinder closed at one end by an integral end plate and partly closed at the other end by an end cap, means for biasing said tubular member to one position in said cylinder, an adjustable stop screw carried by the one lever and cooperating with said end plate to limit the movement of said one lever due to its bias to the position in which the associated braking bar occupies a predetermined non-braking position, a bolt pivotally connected at one end to the other lever and extending into said tubular member through said end cap, a nut on said bolt within said tubular member, a sleeve in said tubular member cooperating with said nut and said cap to limit the rotation of said other lever in the direction to move the associated braking bar toward the track rail to the position in which the associated braking bar occupies a predetermined braking position, a spring in said tubular member surrounding said bolt within said sleeve for assisting the force of gravity in rotating said other lever in the direction to move said braking bar away from the track rail, and means on said bolt cooperating with said end cap to limit the rotation of said other lever in the direction to move the associated braking bar away from the track rail.

5. Railway braking apparatus comprising two braking bars located on opposite sides of a track rail and adapted to be moved toward and away from the rail into braking and non-braking positions, a first lever for supporting one of said braking bars, said first lever being pivotally mounted at one end on a fixed pivot pin and having its free end inclined upwardly and extending away from said rail a second lever pivotally mounted intermediate its ends on said pivot pin and having one end inclined upwardly and extending away from said rail in a position to support the other braking bar and having its other end inclined downwardly and extending away from the rail below the free end of said first lever, the parts being so proportioned that said braking bars are biased to their non-braking positions by gravity, a fluid pressure motor for operating the levers, a fixed cylinder mounted in a substantially vertical position between said levers, a tubular member in said cylinder having one end closed by an integral end plate and the other end partly closed by an end cap, means in said cylinder for biasing said tubular member to one position, an adjusting screw screwed through the first lever and cooperating with said tubular member at said end plate to limit the rotation of said first lever in the direction to move the associated braking bar away from the rail to the position in which the associated braking bar occupies its non-braking position, a bolt pivotally attached to said other end of said second lever and extending into said tubular member through said end cap and provided with means which cooperates with said end cap to limit the rotation of said second lever in the direction to move the associated braking bar away from the rail to the position in which the braking bar occupies its non-braking position, a nut on said bolt within said tubular member, a compressed spring sur-

rounding said bolt between said nut and said end cap to assist the force of gravity in biasing said second lever to the position in which the associated braking bar occupies its non-braking position; and a sleeve in said tubular member cooperating with said nut to limit the rotation of said second lever in the direction to move the associated braking bar toward the track rail to the position in which the braking bar occupies its braking position, the parts being so proportioned that when said second lever occupies the position in which the associated braking bar occupies its braking position and the piston of said fluid pressure motor occupies its projected position said first lever will occupy the position in which the associated braking bar occupies its braking position.

6. Railway braking apparatus comprising two braking bars disposed on opposite sides of a track rail and movable toward and away from the rail into braking and non-braking positions, two pivoted levers supporting said two braking bars respectively, a fluid pressure motor operatively connected with the levers for moving the braking bars to their braking positions, the parts being so proportioned that the braking bars are biased to their non-braking positions by gravity, a fixed bracket formed with a cylindrical portion which is disposed between said levers, a cylindrical member screwed onto one end of said cylindrical portion and forming with the cylindrical portion a cylinder of adjustable length, a first inwardly extending annular flange on said cylindrical portion at the end opposite to said cylindrical member forming a first shoulder, a second inwardly extending annular flange on said cylindrical member at the end opposite said cylindrical portion forming a second shoulder which faces said first shoulder, a tubular member in said cylinder closed at one end by an end plate provided with a flange forming a third shoulder which is adapted to align with said second shoulder, an end cap on the other end of said tubular member forming a fourth shoulder which is adapted to align with said first shoulder, a compressed coil spring surrounding said tubular member within said cylinder, two washers in said cylinder one disposed between one end of said spring and said first and fourth shoulders and the other disposed in said tube between the other end of said spring and said second and third shoulders, means carried by the one lever and cooperating with said end plate to limit the movement of said one lever due to its bias to the position in which the associated braking bar occupies its non-braking position, and means attached to the other lever and cooperating with said end cap to limit the movement of said other lever due to its bias to the position in which the associated braking bar occupies its non-braking position.

7. Railway braking apparatus comprising two braking bars disposed on opposite sides of a track rail and movable toward and away from the rail into braking and non-braking positions, two pivoted levers supporting said two braking bars respectively, a fluid pressure motor operatively connected with the levers for moving the braking bars to their braking positions, the parts being so proportioned that the braking bars are biased to their non-braking positions by gravity, a fixed bracket formed with a cylindrical portion which is disposed between said levers, a cylindrical member screwed onto one end of said cylindrical portion and forming with the cylindrical portion a cylinder of adjustable length, a spring disposed

in said cylinder and having an initial compression which depends upon the adjusted position of said cylindrical member, a second member axially movable in said cylinder in both directions and biased to one position by said spring, means carried by the one lever and cooperating with said second member to limit the movement of said one lever due to its bias to the position in which the associated braking bar occupies its non-braking position, and means secured to the other lever and cooperating with said second member to limit the movement of said other lever due to its bias to the position in which the associated braking bar occupies its non-braking position.

8. Railway braking apparatus comprising two braking bars disposed on opposite sides of a track rail and movable toward and away from the rail into braking and non-braking positions, two pivoted levers supporting said two braking bars respectively, a fluid pressure motor operatively connected with the levers for moving the braking bars to their braking positions, the parts being so proportioned that the braking bars are biased to their non-braking positions by gravity, a fixed bracket formed with a cylindrical portion which is disposed between said levers, a cylindrical member screwed onto one end of said cylindrical portion and forming with the cylindrical portion a cylinder of adjustable length, a spring disposed in said cylinder and having an initial compression which depends upon the adjusted position of said cylindrical member, a second member axially movable in said cylinder in both directions and biased to one position by said spring, means carried by the one lever and cooperating with said second member to limit the movement of said one lever due to its bias to the position in which the associated braking bar occupies its non-braking position, means secured to the other lever and cooperating with said second member to limit the movement of said other lever due to its bias to the position in which the associated braking bar occupies its non-braking position, a pair of ribs formed on said cylindrical portion, a plurality of recesses formed in said cylindrical member, and a locking plate secured to said cylindrical portion between said ribs and cooperating with one of said recesses to lock said cylindrical member in an adjusted position.

9. Railway braking apparatus comprising two braking bars disposed on opposite sides of a track rail and movable toward and away from the rail into braking and non-braking positions, two pivoted levers supporting said two braking bars respectively, a fluid pressure motor operatively connected with the levers for moving the braking bars to their braking positions, the parts being so proportioned that the braking bars are biased to their non-braking positions by gravity, a fixed bracket formed with a cylindrical portion which is disposed between said levers, a cylindrical member screwed onto one end of said cylindrical portion and forming with the cylindrical portion a cylinder of adjustable length, a spring disposed in said cylinder and having an initial compression which depends upon the adjusted position of said cylindrical member, a second member axially movable in said cylinder in both directions and biased to one position by said spring, means carried by the one lever and cooperating with said second member to limit the movement of said one lever due to its bias to the position in which the associated braking bar occupies its non-braking position, means secured to the other lever and cooperating with said second member to limit the movement of said other lever due to its bias to the position in which the associated braking bar occupies its non-braking position.

member to limit the movement of said other lever due to its bias to the position in which the associated braking bar occupies its non-braking position, a plurality of spaced recesses formed in said cylindrical member, and means secured to said cylindrical portion and cooperating with one of said recesses to lock said cylindrical member in an adjusted position.

10. Railway braking apparatus comprising two braking bars located on opposite sides of a track rail, two pivoted levers supporting said two braking bars respectively, a fluid pressure motor for operating said levers to move said braking bars

toward the track rail to braking positions, said levers being biased by gravity to move said braking bars away from the track rail to non-braking positions, a fixed cylinder disposed between said levers, a tubular member biased to one position within said cylinder, and adjustable means secured to said two levers and cooperating respectively with the opposite ends of said tubular member to limit the rotation of said levers due to their gravity bias to positions in which said braking bars occupy the desired non-braking positions.

HERBERT L. BONE.
